SURFACE FINISHING MACHINE

Ray E. Ponder, St. Louis, Mo., assignor to United
Wood Heel Company, St. Louis, Mo., a corpora-
tion of Delaware

Application December 19, 1940, Serial No. 370,771

28 Claims. (Cl. 51—144)

This invention relates to surface finishing machines; and has special reference to machines for imparting a surface finish to portions of the outer surfaces or to the entire outer surfaces of shoe heels or other articles.

One object of the invention is to provide a machine having an endless surface finishing belt and mechanisms for operating the same continuously and at effective speed, in cooperation with a resilient backing device for contouring the continuously moving belt complementarily to the sides and back of the heel or other article upon which the belt is operating, mechanism including a work holding jack for picking-off or engaging and moving the work to position for operation of the finishing belt thereon, and mechanism for operating the jack to turn the article to present the entire outer surface thereof to the belt for finishing action; or, as in the case of heels of certain designs, to present the entire side and rear surfaces thereof to the belt for its effective action to provide the proper surface finish on said side and rear surfaces.

Another object is to provide a machine including a continuously moving finishing belt, and a jack mechanism for holding the heel against said belt, in combination with means for coordinating the operations and movements of the belt and jack mechanism to form continuously and completely finished surfaces on French heels or other heels throughout the sides and rear thereof including the outer surfaces of the forward extensions at the attaching ends of the heels, thereby avoiding subsequent finishing operations along the outer sides of said extensions.

Another object of the invention is to provide mechanism for operating the heel holding jack to turn the heel to different positions for operation of the finishing belt thereon to round or spool the lower portions of the corners formed at the intersection of the breast wall of the heel with the lateral sides thereof.

Another object of the invention is to provide a machine embodying the foregoing mechanisms, with means for coordinating the operations thereof so that the machine may be operated continuously to form finished surfaces on great quantities of heels of different styles at maximum speed and within a minimum of time.

Other objects will appear from the following description, reference being made to the annexed drawings illustrating a preferred embodiment of the invention and in which—

Fig. 1 is a front elevation of the machine with parts of the casing structure removed.

Fig. 2 is a right-hand side elevation of the machine with parts in section.

Fig. 3 is a left-hand side elevation of the machine.

5 Fig. 4 is an enlarged front elevation of the principal portion of the machine, the cover guard being in open position to show the work feeder or holder at the pick-off position of the jack supported and operated thereby.

10 Fig. 5 is a view similar to Fig. 4 and showing the feeder or holder in open position for hand feeding.

Fig. 6 is a sectional view on the line 6—7 of Fig. 2, looking in the direction of the arrow at 6, 15 showing the feeder or holder in the pick-off position of the jack.

Fig. 7 is a sectional view on the same line looking in the direction of the arrow at 7 and showing the cams for rotating the jack to present the 20 sides and back of a heel to the belt for surface finishing.

Fig. 8 is a view similar to Fig. 7 showing more clearly the means for adjusting the heel holder.

Fig. 9 is a sectional view on the line 9—9 of 25 Fig. 1 showing the work holding jack and heel therein at the pick-off position of the jack at the top of its stroke.

Fig. 10 is a similar view showing the jack at the discharged position thereof at the bottom of 30 its stroke.

Fig. 11 is a sectional view on the line 11—11 of Fig. 10.

Fig. 12 is a perspective view of the restoring 35 lever for the supporting slide in which the pick-off pivot pin is mounted.

Fig. 13 is a perspective view of the cam arm for controlling turning movement of a heel jack to present the sides and back of a heel to the finishing belt.

40 Fig. 14 is a perspective view of the floating carriage for the pad holder that causes the pad to follow the varying contour of the heel to shape the continuously moving belt to form the proper surface finish.

45 Fig. 15 is a perspective view of one of the end pivot plates for supporting the floating carriage.

Fig. 16 is a sectional view on the line 16—16 of 50 Fig. 2, showing the means for adjusting the feed holder properly in relation to the pick-off position thereof.

Fig. 17 is an enlarged top plan or sectional view on the line 17—17 of Fig. 4, showing the heel feed holder and the pivoting jack in the pick-off position.

55 Fig. 18 is a perspective view of the resilient

backing pad for the endless belt and which shapes said belt according to the outer surface of the article to be given a surface finish.

Fig. 19 is a view showing the ratchet feed device for the backing belt constituting a part of the support for the finishing belt.

Fig. 20 is a sectional view on the line 20-20 of Fig. 21, showing particularly the resilient backing pad and backing belt and the floating carriage mechanism.

Fig. 21 is an enlarged horizontal sectional view on the line 21-21 of Fig. 4 showing the upper portion of the machine.

Fig. 22 is an enlarged sectional view on the line 22-22 of Fig. 21, showing the floating carriage mechanism.

Fig. 23 is a sectional view on the line 23-23 of Fig. 21, showing the floating carriage mechanism.

Fig. 24 is a detached perspective view of the floating pad holder.

Fig. 25 is a perspective view of the actuator controlling rounding-in movement of the resilient pad.

Fig. 26 is an enlarged top plan view of the feed holder mechanism in pick-off position, which is the position of the holder mechanism when the jack removes or picks-off the work therefrom.

Fig. 27 is a front side elevation of the feed holder mechanism in the same position as in Fig. 26.

Fig. 28 is a sectional view on the line 28-28 of Fig. 26.

Fig. 29 is a sectional view on the line 29-29 of Fig. 27.

Fig. 30 is a sectional view on the line 30-30 of Fig. 27.

Fig. 31 is a front elevation of the feed holder at the hand feeding position.

Fig. 32 is a sectional view on the line 32-32 of Fig. 33 showing a portion of the feed holder mechanism.

Fig. 33 is a left-hand side elevation of the mechanism shown in Fig. 31.

Fig. 34 is a sectional view on the line 34-34 of Fig. 26.

Fig. 35 is a sectional view on the line 35-35 of Fig. 33.

Fig. 36 is a sectional view on the line 36-36 of Fig. 27 showing details of the feed holder mechanism.

Fig. 37 is an active diagram showing different positions of one type of heel during rotation thereof in relation to the floating pad and the finishing belt.

Fig. 38 is a view showing another and improved form of gearing and cam mechanism for turning the work in coordination with the movement of the resilient pad and the continuously moving finishing belt.

Fig. 39 is a sectional view on the line 39-39 of Fig. 38.

Fig. 40 is a rear elevation of a resilient pad showing means for varying the contour of the effective surface thereof for shaping the continuously moving finishing belt in accordance with the different curvatures of the work.

Fig. 41 is a sectional view on the line 41-41 of Fig. 40.

Fig. 42 is an active diagram in the manner of Fig. 37 showing different positions of another type of heel or other article during complete rotation thereof about its longitudinal axis to present the entire outer surface thereof to the finishing belt.

Fig. 43 is a view similar to Figs. 7 and 8 showing a construction for turning the article to present the entire outer surface thereof to the finishing belt for surface finishing.

Fig. 44 is a perspective view showing a type of shoe heel which the mechanism of Fig. 43 is designed to support and turn to present the entire outer surface thereof to the finishing belt.

The entire operating mechanism of the machine is supported by the main frame 1 upon which a driving motor 2 is mounted. The belt 3 driven by the motor constantly rotates a shaft, supported at the upper end of the frame, when said motor is running. The shaft 4 has a pulley 5 attached thereto and engaged by a finishing belt 6 which also engages a lower pulley 7 supported near the lower end of the frame. The belt 6 may be a sanding or abrading belt, or any type of belt for forming a desired surface finish on part or all of the outer surface of the article to be surface finished. The belts 6 are removable and replaceable, so that any type of belt may be replaced by another of the same or of different type. The pulleys 5 and 7 and the belt 6 are enclosed within a casing. One side of the casing comprises hinged doors 8 and 9 which may be closed for protective purposes and opened to afford access to the pulleys and the abrading or sanding belt. The interior of the casing may be provided with an upper partition 10 approximately along the adjacent edges of the doors 8 and 9, and a partition 11 in the lower end of the casing above the pulley 7. Thus, either door 8 or 9 may be opened to afford access to the pulley 6 enclosed thereby; and, when both doors are closed, the belt 6 is covered and guarded. The door 8 also affords access to that part of the mechanism acting to conform the belt 6 to the contour and curvature of the wood heels being sanded by said belt (Fig. 4).

A carriage 12 is mounted for vertical sliding movements in the frame 1. The carriage 12 is guided by the frame 1 (Fig. 21) and is reciprocated vertically by intermittent rotation of a shaft 13 and attached crank 14 connected with said frame 12 by a link 15 (Figs. 2 and 3). The shaft 13 is operated intermittently and is rotated exactly or approximately one complete revolution at each operation thereof. Any suitable and known mechanism with known connections (not shown) may be used to rotate said shaft 13 in this manner, and to effect intermittent starting and stopping thereof. In this machine, the unoperated, which is to say the starting and stopping, position of the shaft 13 is that in which the carriage 12 is midway of the ends of its movements. A flexible connection 16 supported on rollers 17 has one end attached to the carriage 12 and its opposite end supporting a counterweight 18 to cooperate with the driven connections for operating the carriage 12 and to stabilize such operation.

A detent 19 (Figs. 4, 5 and 7) is mounted on a pivot 20 carried by a part 21 rigid with the carriage 12 so that, when said carriage is moved vertically, the detent 19 is also moved vertically. The detent 19 may be held in different adjusted positions about the pivot 20 by an adjusting screw 22. As before stated, the stopped or unoperated position of the carriage 12 is midway of the ends of its vertical movement, from which position it is moved upwardly to the upper end of its stroke, and thence downwardly to the lower end of its stroke, and thence upwardly to its unoperated position midway of the ends of its stroke. Up-

ward movement of the carriage 12 causes the ⁵ ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ A plate 68 is attached to the upper side of the tie 66 by a clamping screw 69 whereby the plate 68 may be secured in different adjusted positions to accommodate the machine for heels of different sizes. A bracket 70 is secured to the plate 68 by a fastening screw 71 and supports an upwardly extended post 72 to which a bifurcated abutment 73 is connected by a pivot 74. The abutment 73 is slightly wider than the post 72 and is pressed against the attaching end of the heel by action of the spring 67 when the heel is placed in the holder comprising the parts 31, 41 and the arms 33 and 35. The abutment 73, being spring actuated, is held yieldingly against the attaching end of the heel and thereby prevents the heel from becoming dislocated during movement of the holder by the detent 19 acting against the roller 23, as before described. An angular spring 75 attached to the arm 28 (Fig. 31) engages one corner at the breast wall of the heel near the top lift end and affirmatively cooperates with the parts 31, 41, the arms 33 and 35 and the spring actuated abutment 73 to locate and hold the heel in proper position in the holder for engagement by the jack. The support 26 is a part of a frame 76 including the sleeve 56 mounted on the support 57. This frame may be adjusted and held in different angles of inclination from the support 57 by screws 77 held in brackets 18 attached to the frame 1 (Figs. 7 and 16) in order to locate the swinging heel holder in proper position to move the heel to the jack which removes the heel from the heel holder and turns the heel for operation of the abrading or sanding belt 6.

An angular bracket 79 constituting a support for the jack mechanism is attached to the sliding carriage 12 (Figs. 9, 10 and 11). A rod 80 (Figs. 11 and 13) is supported for turning movements in the upper part of the bracket 79 and has rigid with its inner end a head 81 formed with two integral spaced pointed pins or lugs 82 adapted to become embedded in the attaching end of the heel when the heel is moved by the holder inwardly in the manner already described. The outer end of the rod 80 is rigidly attached to an arm 83 which has rigid therewith an outwardly extended pin 84 supporting a roller 85 adapted to be moved into and out of a cam slot 86 (Fig. 7) formed in a rigid plate 87. An arm 88 is rigid with the pin 84 and supports a roller 89 adapted to be engaged in a long cam slot 90 formed in a rigid plate 91.

In Fig. 7, the carriage 12 is at the end of its upward movement and the roller 85 is in the upper part of the cam 86. When the carriage 12 moves downwardly, the crank device comprising the rod 80, the arm 83, pin 84 and arm 88 will be oscillated slightly by the cam slot 86 during initial portion of the downward movement of the carriage 12. After the carriage 12 has moved downwardly a slight distance, the roller 89 will be engaged in the cam slot 90, as should be understood by reference to Fig. 7, and shortly thereafter the roller 85 is carried beyond the cam slot 86, leaving the cam slot 90 free to turn the crank device and thereby turn the jack head 81, which turns the wood heel supported thereby about its longitudinal axis. Still further downward movement engages the roller 85 in a cam slot 86' in a rigid plate 87' supported in the same vertical plane as the plate 87, and shortly thereafter the roller 89 leaves the cam slot 90, leaving the cam slot 86' and roller 85 free to turn further the jack rod 80 and thereby the heel 30 supported in the jack. This turning of the heel

about its longitudinal axis causes the abrading or sanding belt to round or spool one corner of the heel adjacent to the top lift end and continuously act upon the adjacent side, rear and opposite side and opposite corner of the heel to impart to said sides and back a smooth surface finish and to said last named corner a rounded spooled finish.

A slide 92 is supported by the rigid bracket 79 by pin and slot connection 93 and a similar pin and slot connection 94. A jack pin 95 is attached to the slide 92 and is moved thereby to engage in the center or vertical axis of the top lift end portion of the heel 30 when the holder moves the heel to position for engagement by the jack (Figs. 9 and 17). A spring 96 connects the pin 93 with the rigid bracket 79 and actuates said slide 92 in a direction to move the jack pin 95 toward the head 81. Extent of such movement may be limited by the length of the slots through which the pins 93 and 94 extend. The slide 92 is held in its outward position in opposition to the spring 96 by a latch detent 97 attached to the pivot 98 carried by the bracket 79 and adapted to engage a shoulder 99 on the slide 92. A finger 100 attached to the pivot 98 at the opposite side of the bracket 79 from the latched detent 97 is actuated by a spring 101 to cause the latch 97 to engage the shoulder 99. At about the end of the upward movement of the carriage 12, the finger 100 engages an adjustable abutment 102 mounted in a rigid support 103 attached to the frame 1, and said finger is thereby moved to turn the pivot 98 and thereby disengage the latch 97 from the shoulder 99. This occurs just at the time that the heel 30 is properly located for engagement by the jack pins 82 and 95. When the latch 97 is thus disengaged from the slide 92, the spring 96 immediately moves the slide 92 to engage the pin 95 in the vertical axis of the heel at the top lift end thereof, and this action embeds the two spaced pins 82 in the attaching end of the heel. The heel is thus engaged in the jack preparatory for downward movement of the carriage 12 during which the jack is turned by the crank device (Fig. 13) operated by the cams 86, 90 and 86', as before described.

When the heel holder frame 27 is moved inwardly by the detent 19 operating against the roller 23 as before described, said holder frame is stopped in proper position relative to the jack, so that the jack pins 82 will engage properly in the attaching end of the heel at diametrically opposite sides of the vertical axis thereof, and the jack pin 95 will engage in the top lift end of the heel at the vertical axis thereof by an adjustable stop 104 on the heel holder frame abutting against the bearing 80' for the rod 80. This occurs just before the latch 97 is released from the shoulder 99 by the abutment 102 and during the final portion of the upward movement of the carriage 12 to which the jack is attached. When the latch 97 is released from the shoulder 99, the spring 96 immediately moves the slide 92 and thereby the pin 95 to engage said pin in the lift end of the heel and force the heel slightly in the opposite direction to engage the pins 82 in the attaching end of the heel.

As before stated, the springs 61 tend to move the frame 58 downwardly along the posts 59. When the frame 27 is in its unoperated position (Figs. 31 and 32), a roller 105 supported by said frame 58 is seated against a rigid cam 106 attached to the support 57, and said frame is

thereby supported in its raised position with the abutment 73 in position to engage against the attaching end of any heel 30 placed in the heel holder. A finger 107 projecting from the bail 63 engages a projection 108 rigid with the frame 27 when said frame 27 is moved inwardly as described a slight distance during which the inward movement of the roller 105 moves downwardly along the cam 106 to effect such engagement of the finger 107 with the rigid projection 108. This latches the sliding frame 58 in its raised position and permits the spring 67 to hold the pivoted abutment 73 against the attaching end of the heel. At about the time the jack pins 82 and 95 are engaged in the opposite ends of the heel in the manner already described, the pivoted frame comprising the bails 63 and 64 is swung to the left as seen in Fig. 33 far enough to disengage the finger 107 from the rigid projection 108, thereby moving the abutment 73 out of engagement with the attaching end of the heel. When the finger 107 is disengaged from the projection 108, the springs 61 move the frame 58 along the posts 59 and into abutting contact with the cushions 62, thereby moving the abutment 73 laterally beyond the heel that is now engaged and held by the jack pins 82 and 95 (Fig. 17).

As before described, when the holder frame 27 having a heel 30 mounted thereon is moved inwardly by upward movement of the detent 19 as described, the stop 104 on said frame 27 engages the bearing 80' for the rod 80 and said frame is thereby stopped in the exact position for proper engagement of the pins 82 and 95 with the attaching and top lift ends respectively of the heel 30. Immediately after the heel 30 has thus been located in proper position for engagement of the pins 82 and 95 therewith, the latch 97 is released from the shoulder 99 by the abutment 102 as described. When the latch 97 is released from the shoulder 99, the spring 96 instantly moves the slide 92, thereby moving the pin 95 into the slot 28' and into engagement with the top lift end of the heel 30 and driving the heel 30 longitudinally of its axis a distance to engage the attaching end of said heel against the head 81 and to embed the pins 82 in the attaching end of the heel. This movement of the heel 30 longitudinally toward the right and to the position shown in Fig. 9 causes the heel to move the abutment 73 laterally (toward the left as seen in Fig. 33), thereby swinging the frame comprising the bails 63 and 64 far enough to disengage the finger 107 from the rigid projection 108. When the heel 30 is moved longitudinally in this way, the wide attaching end thereof slides along the angular portions 33 and 35 of the levers 32 and 34 which continue to hold the attaching end of the heel in substantially the same axial position during its sliding movement while the top lift end of the heel is substantially disengaged from the parts 31 and from the spring 75. The heel is now held in proper position and positively prevented from becoming dislocated by the pins 82 and 95 which are embedded in opposite ends of the heel. When the finger 107 is disengaged from the projection 108 by lateral swinging movement of the bail frame 63, 64, the springs 61 immediately retract to move the frame 58 along the posts 59, thereby removing all pressure from against the attaching end of the heel by the abutment 73. When the abutment 73 is disengaged from the attaching end of the heel 30, the spring 67 re-

tracts, thereby swinging the bail frame 63, 64 to position to place the finger 107 below the projection 108 at the lowest point where the frame 58 comes to a stop against the shock absorbers 62. As the carriage 12 descends and moves the detent 19 downwardly from the roller 23, the spring 52 raises or swings the carriage 27 upwardly and outwardly to its position against the sleeve 56. During such upward and outward movement of the frame 27 by the spring 52, the roller 105 rides along the cam 106 and thereby raises the frame 58 along the posts 59. While the frame 58 is being raised the finger 107 contacts the projection 108. Said finger and projection are beveled, leaving the finger free to slide along the side of the projection and thereby swing the bail frame 63, 64 laterally. When the finger 107 rises above the projection 108, said finger again becomes engaged upon said projection by action of the spring 67 in position to engage said projection 108 upon slight downward movement of the frame 58. Engagement of the finger 107 upon the projection 108 latches the frame 58 in its raised position until said finger 107 is again released from the projection 108 by longitudinal movement of the heel 30 by the jack pin 95, as described.

During downward movement of the carriage 12, the heel 30 is turned about its longitudinal axis to cause the abrading or sanding belt 6 to impart a smooth surface finish to the sides and rear of the heel and also to spool or round off the breast corners of the heel near the top lift end thereof. This turning movement is effected by the cam arm device (Fig. 13) and the cams 86, 90 and 86' engaging the rollers 85, 89, and 85, successively, thereby turning the jack rod 80 as before described. After the heel has been spooled and surface finished and just before the carriage 12 reaches the end of its downward stroke, the slide 92 is moved longitudinally to release the heel from the jack pins 82 and 95. A restoring lever 109 is pivoted on the bracket 79 (Figs. 9, 10 and 12) and has a bifurcated end 110 engaging the pin or screw 94 attached to the slide 92 and operating through a complementary slot in the bracket 79. A roller 111 supported by the lever 109 engages a rigid cam 112 during the final portion of the downward movement of the carriage 12. The cam 112 against which the roller 111 operates swings the lever 109 to move the slide 92 in opposition to the spring 96 and to a position in which the latch 97 engages the shoulder 99, thereby holding the slide 92 in its retracted or outward position to receive another heel from the holder frame 27 during the next upward movement of the carriage 12. A pair of stripper fingers 113 are attached to the bifurcated upper end of an upwardly extended arm 114 integral with the inner end of the slide 92. These stripper fingers 113 are at opposite sides of the jack head 81; and, when the slide 92 is moved outwardly by the lever 109, said fingers 113 engage the attaching end of the heel 30 and push said heel away from and out of engagement with the pins 82. Outward movement of the slide 92 also moves the pin 95 through a stripper arm 115 rigid with the bracket 79 and thereby detaches the top lift end of the heel from said pin 95. Thus the heel is entirely detached from the jack and drops by gravity into an inclined chute 116 attached to the bracket 79. The heel slides downwardly along the inclined chute 116 to a point of discharge.

To stop the frame 27 positively and prevent said frame from following the jack during downward movement thereof and prevent the parts 33 and 35 from contacting the abrading or sanding belt 6, a rigid abutment 117 is attached to the frame 1. This abutment leaves the frame 27 free to move to a position in which the stop 104 engages the bearing 80', but will engage the frame 27 and prevent the same from following the jack any substantial distance during downward movement of the jack. This prevents the parts 33 and 35 from wearing or damaging the abrading or sanding belt, and leaves the spring 52 free to return the frame 27 to its initial or starting position against the sleeve 56 without restraint. The speed of such return movement of the frame 27 by the spring 52 is controlled by the speed of downward movement of the detent 19.

A number of air jets may be automatically directed against the heel 30 and against the jack and the sanding belt during operation thereof in order to remove the abraded particles and to enable them to be withdrawn from the machine through a suction pipe 118 opening from the top of the casing in which the sanding belt operates. A rigid extension 119 from the bracket 79 is attached to the upper ends of a number of air pump cylinders 120 (Figs. 2, 4 and 5), which are thereby reciprocated along their piston rods 121 and caused to function as air pumps in a manner well known. These air pumps are of known construction and operation, enclosing pump pistons (not shown) which, when reciprocated relatively within the cylinders 120, will eject air from the discharge ends of said cylinders. A tube 122 opens from the upper end of each of the cylinders 120, and said tubes open into discharge nozzles 123 rigid with the extension 119. The ends of the nozzles 123 are directed generally toward the heel in the jack, which is to say toward the jack and adjacent to the sanding belt 6. These jets of air are discharged during downward movement of the jack and heel and during the time that the heel is being abraded or sanded by the belt 6. The jets of air function to dislodge and cause the abraded particles to move upwardly and for the most part to be withdrawn from the machine through the suction pipe 118.

A frame 124 (Figs. 5, 14 and 21) has one end pivoted to the free ends of a pair of end pivot plates 125. These pivot plates are held in relatively rigid relationship by a tie-rod 126 passing through said plates and through an interposed sleeve 127 against which said plates are clamped by said tie-rod (Fig. 23). The ends of said pivot plates opposite from the ends to which the frame 124 is pivoted are connected by a pivot 128 with a bracket 129 mounted on a pivot 130 rigid with the vertically reciprocating carriage 12. Thus, the frame 124 is capable of movement about its supporting pivots 131, securing said frame 124 to the end plates 125, and said plates 125 are capable of movement about their pivot 128, and the bracket 129 is capable of oscillation about its pivot 130.

A resilient backing pad is mounted on a pivot 132 (Figs. 18 and 21). The body 132' of said pad has on its rounded side that is toward the sanding belt 6 a resilient surface covering 133. The pivot 132 is mounted in a bracket 134 attached to the frame 124. An actuator for said pad comprises a bifurcated member 135 mounted on a pivot 136 supported by the bracket 134. A spring 137 on the pivot 136 and attached to the bracket 134

presses one end of the pad 132' toward the belt 6. The actuator 135 engages the pad 132' beyond the pivot 132 and, during reciprocation of the carriage 12, engages rigid cams 138 and thereby turns the pad 132' about the pivot 132 in opposition to the spring 137 to vary the contour of the adjacent portion of the belt 6.

The end of the frame 124 opposite from the pivots 131 is connected by a number of springs 139 with an arm 140 attached to the carriage 12 and by a spring 141 with an arm 142, also attached to the carriage 12. These springs 139 and 141 function to hold rollers 143, 144 and 145 mounted on the frame 124 in contact with cam rails 146, 147 and 148, respectively. These cam rails along which said rollers operate will oscillate the frame 124 about its pivots 131 and also impart more or less oscillating movements to the pivot end plates 125 and to the pivot device 129 to cause the curved padded surface of the pad device 132' to move to positions complementary to the curved surfaces of the heels operated against the sanding belt by the jack mechanism as before described.

A backing belt 149 is interposed between the elastic pad and the sanding belt 6. The backing belt 149 is of soft and pliable material, such as plush, and operates over an upper roller 150 and a lower roller 151 and between the elastic pad and the sanding belt (Fig. 4). The rollers 150 and 151 are supported by the vertically reciprocating carriage 12 and are moved vertically with the heel jack, the pad 132' and the mechanism for supporting and operating said pad, and which has already been described. A ratchet wheel 152 is attached to the axle 153 to which the lower roller 151 is attached. A lever 154 is pivoted on the axle 153 and supports a pivoted pawl 155 engaging the ratchet wheel 152 (Figs. 5, 6 and 19). At about the end of the downward movement of the carriage 12 the lever 154 engages and is operated by an adjustable abutment 156 to rotate the ratchet wheel 152 and thereby the roller 151 a part of a revolution. This moves the belt 149 to bring other contacting portions of said belt between the elastic pad 132' and the sanding belt 6. During upward or return movement of the carriage 12, the lever 154 is moved out of engagement with the abutment 156 and returns to initial unoperated position against a support 157. Reverse turning of the ratchet 152 is prevented by a spring detent 158.

The bracket 134 supports an adjustable abutment 159 for the body of the pad 132' to limit extent of turning movement of said pad by the spring 137 (Figs. 21 and 24). When the actuator 135 is beyond and out of engagement with the cams 138, the body of the pad 132' is engaged with the end of the abutment 159 and held thereby against further movement by the spring 137. One of the pivot end plates 125 is connected by a spring 160 with the bracket 129 in a manner to cooperate with the springs 139 and 141 to hold the pivotally connected parts comprising the frame 124 in proper relationship to press the pad 132' against the belt 149 and to cause the rollers 143, 144 and 145 to press against and operate properly along the cams 146, 147 and 148. These springs yield when the frame 124 is oscillated laterally or moved longitudinally by the cams 146, 147 and 148 in coordination with the movement of the actuator 135 by the cams 138. These oscillating movements of said parts oscillate the pad 132' to move the curved surfaces thereof in coordination with the complementary

curved surfaces of the heel 30 during descent of the jack that supports and turns the heel in proper relationship to the belt 6.

An alternative form of mechanism for turning the jack rod 80 is shown in Figs. 38 and 39. As there shown, the cams 86, 90 and 86' are displaced by a substituted cam plate 161 having an inclined cam slot 162 formed at its upper end with a quick turning cam portion 163 and at its lower end with a reverse quick turning cam portion 164. In this alternative form of mechanism, a pinion 165 is attached to the jack shaft 80 and meshes with a pinion 166 attached to a fixed stud shaft 167 supported by the bracket 79. An arm 168 attached to the pinion 166 on the shaft 167 supports a roller 169 engaged in the cam slot 162-163-164. In the upper position of the carriage 12 that supports the jack, the roller 169 is engaged in the upper portion of the cam slot 162 beyond the quick turning portion 163.

Fig. 37 diagrammatically shows various positions of the heel in the jack, beginning with the position of the heel when it is first engaged in the jack and ending with the position of the heel after the surface finish has been formed, including the spooling positions of the heel and the discharge position of the heel from the jack.

The heel 30, when first engaged in the jack, is in approximately the position shown at A, in which the breast wall of the heel faces downwardly. During the short initial downward movement of the carriage 12, the roller 85 operates in the cam 86, thereby turning the jack rod 80 which turns the heel 30 to the position shown at B. In this position, that breast wall corner of the heel which is adjacent to the belt 6 is spooled or rounded for a short distance upwardly from the top lift end of the heel. During this initial downward movement, the actuator 135 engages and is operated by the cam 138 to move the pad 132' forwardly toward the heel, which movement causes the sanding belt 6 to operate only against and along that portion of the corner of the heel to be rounded or spooled. Further downward movement of the carriage 12 carries the actuator 135 beyond the upper cam 138, and this occurs when the roller 89 attached to the arm 88 enters and moves along the upper portion of the cam 90. The jack shaft 80 is then turned during further downward movement of the carriage 12 and by further downward movement of the roller 89 along the cam 90 to turn the jack shaft 80 and thereby turn the heel 30 along and through the positions C, D and E. During this movement the rollers 143, 144 and 145 operate along their cams 146, 147 and 148, respectively, and cooperate with the springs 139, 141 and 160 to move the pad 132' and cause said pad to present surfaces thereof curving complementarily to the curved surfaces of the heel 30 along the sides and rear thereof. When the roller 85 enters the cam 86' (Fig. 8), the pad 132' is turned to the position F. At this time, the actuator 135 engages the lower cam 138 and, in cooperation with the springs 139, 141 and 160, shapes the belt 6 as required to spool or round the breast corner of the heel at the top lift end thereof, as shown at the position F, symmetrically with the opposite spooled and rounded corner. After a complete surface finish has been imparted to the heel and the corners have been spooled and rounded, the roller 111 engages and is operated by the cam 112. This operation of the lever 109 by the roller 111 operating against the cam 112 moves the slide 92 from the position shown in Fig. 9 to the position shown in 75

Fig. 10, causing the strippers 113 and 115 to disengage the heel from the pins 82 and 95, respectively, leaving the heel free to drop, as shown at G. The released heel drops to the chute 116 and is discharged from the machine.

A modified form of pad for shaping the abrading or sanding belt 6 in conformity with the curvature of the sides and rear of the heel and the corners thereof to be rounded or spooled, is shown in Figs. 40 and 41. This pad comprises a back portion 170 mounted for oscillating movements on the pivot 132 supported by the bracket 134. A resilient or flexible surface covering 171 has its ends attached to the ends of the backing portion 170 by removable and replaceable fasteners 172 and is seated against an inner flexible or resilient and inelastic curved backing 173. A series of adjusting elements 174 for the backing 173 of the elastic surface covering 171 are screwed 20 through the back 170 into abutting contact with the backing 173 to curve and sustain said backing 173 in selected arcs of curvatures, as should be understood by reference to Fig. 41. One end of the backing 173 is engaged with the fasteners 25 172 at one end of the pad and the other end of said backing 173 is free, thereby making it possible to vary the curvature of said backing by varying the positions of the adjusting elements 174. Thus, the curvature of the surface covering 30 171 may be changed in conformity with the curvature of the sides and back of the heel 30, making it easily possible to impart a smooth surface finish to heels of different sizes and forms without changing the pads to provide different 35 sizes of pads for different heels.

In operation, the motor 2 is caused to drive the pulley 5 and thereby the abrading or sanding belt 6, preferably at relatively high speed. The shaft 13 (Figs. 2 and 3) is rotated in the direction indicated by the arrow in Fig. 2, thereby moving the carriage 12 upwardly from its stopped or unoperated position. During this upward movement of the carriage 12, the slide 92 is in its outward position (Fig. 10), permitting the heel to be moved by the holder frame 27 to a position 45 between the pins 82 and 85 in which position the breast wall of the heel faces downwardly, as shown at the position A (Fig. 37). Slight further upward movement of the carriage 12 causes the 50 abutment 102 (Fig. 9) to release the latch 97 from the shoulder 99. When the latch 97 is released from the shoulder 99, the spring 96 immediately moves the slide 92 in a direction to embed the pin 95 in the axis of the top lift end 55 of the heel and to drive the heel longitudinally to embed the pins 82 in the attaching end of the heel. This longitudinal movement of the heel by the pin 95 moves the pivoted abutment 73 (Fig. 33) and thereby the pivoted supporting frame therefor laterally, releasing the finger 107 60 from the projection 108, at which time the springs 61 retract and move the frame 58 along the posts 59.

During the initial portion of the downward 65 movement of the carriage 12, the cam arm (Fig. 13) or the cam actuated gear mechanism (Figs. 38 and 39) turns the jack rod 80 and the head 81 to which the pins 82 are attached, thereby turning the heel continuously from the position shown at B to the position shown at F (Fig. 37), from which latter position the heel is released by the jack and drops to the discharge chute 116. The release is effected by the roller 111 operating against the cam 112, thereby moving the lever 109 70 to the position shown in Fig. 10. This movement

of the lever 109 moves the slide 92, retracting the pin 95 through the stripper 115 and out of engagement with the top lift end of the heel, and causes the stripper pins 113 to disengage the heel from the pins 82. This leaves the heel free to drop onto the chute 116 as stated. This cycle of operation is repeated intermittently and successively so long as the motor 2 and shaft 13 are in operation.

During descent of the carriage 12, the frame 124 and its pivoted supports 125 and 126 are oscillated by the rollers 143, 144 and 145 operating along the cams 146, 147 and 148 and by the action of the springs 139, 141 and 160. This oscillation of the frame 124 effects the proper oscillation of the resilient backing pad 132'. The actuator 135 operating against the cams 138 and coordinated with the said actuation of the frame 124 forms the rounding in or spooling contour at the start and finish of the sanding or abrading operation. These coordinated and actuated motions all work in conformity with the curvature of the sides, back and rounding in or spooling of the heel 30. This oscillation of the backing pad against the backing belt 149 shapes the abrading or sanding belt 6 in conformity with the curvature of the heel being operated upon by said belt.

The belt 6 may be an abrading or sanding belt, or it may be a burnishing or polishing belt, or any other type of belt appropriate for providing a smooth surface finish upon a shoe heel or other article. Such belts are removable and replaceable and interchangeable so that the machine may be operated to abrade or sand the surfaces of the bodies of shoe heels or other articles. When an abrading or sanding belt is employed, final contour may be given the shoe heels or other articles, as by rounding or spooling portions of the corners thereof, as specifically explained. In such uses of the machine, the shoe heels or other articles are turned less than a complete revolution about their longitudinal axes during the time that they are operated upon by the belt 6. Different styles of shoe heels are now used, some of which are not characterized by corners at the side edges of a breast wall, but are rounded throughout their longitudinal outer surfaces. Such shoe heels or other articles having rounded outer surfaces around their longitudinal axes may be operated upon by this machine to provide smooth or polished surfaces. In such cases the shoe heels or other articles are turned approximately a complete revolution about their longitudinal axes so that the abrading or polishing belt, whichever is used, will operate upon the entire outer surfaces thereof during the turning of the shoe heels or other articles about their longitudinal axes.

A plate 175 (Fig. 43) may be used in substitution for the removable and replaceable plate 161, and these plates are interchangeable one for the other, being secured to the frame of the machine by removable fasteners 176. The plate 175 is formed with an elongated cam slot 177 in which the roller 169 operates to turn the pinion 166 and thereby the pinion 165 and the jack shaft 80 at least one complete revolution during movement of the roller 169 along the cam slot 177 from the upper end to the lower end thereof.

A shoe heel 178 having a continuous outer surface capable of being surface finished by a complete revolution thereof about its longitudinal axis by rotation of the shaft 80 as above described, is shown in Fig. 44. This shoe heel may

be placed in the holder frame and adjusted therein in the same manner as the heel 30. Since the heel 178 does not include the forward projection at the attaching end of the heel, and does not require spooling or rounding of the corners at the side edges of the breast wall, said heel 178 may be turned completely about its longitudinal axis, and the entire outer surface thereof around said axis may be given a surface finish either by an abrading or sanding belt before the heel is covered; or after the heel is provided with an enclosing cover, said cover may be burnished or polished or surface finished by an appropriate belt provided for that purpose. To adapt the machine for these varied uses, it is only necessary to provide interchangeable plates 161 and 175 having appropriate cam slots formed therein for imparting the degree of turning movement required to the shoe heel or article mounted in the jack, in order to finish or polish any portion of the outer surface thereof. The shoe heel 178 shown in Fig. 44 is enclosed by an attached cover 179 which may be finished or polished by an appropriate belt 6 after the body of the heel has been completed.

From the foregoing, it should be apparent that this invention attains all of its intended objects and purposes by novel mechanism arranged and coordinated in a cooperative manner to provide smooth surface finishes on shoe heels or other articles of different sizes and types. The co-operating mechanisms may be properly adjusted and thereafter operated in proper sequence and in proper coordination for this purpose. It is apparent that the invention may be varied in other particulars than those specifically defined herein and within equivalent limits without departures from the nature and principle of the appended claims.

I claim:

1. A surface finishing machine comprising a movable finishing belt, mechanism for clampingly engaging opposite ends of and positively turning an article about a predetermined axis for operation of said belt on the surface of said article around said axis, a device for varying the transverse contour of the belt complementary to the longitudinal contour of the article, a device for holding the article in position for delivery to said mechanism, and means operated in timed relationship with the operation of said mechanism for moving said device to deliver an article to said mechanism in a predetermined position about said axis for rotation about said axis, as aforesaid.

2. A surface finishing machine comprising a movable finishing belt, mechanism cooperating with said belt to support and move longitudinally of the belt an article for operation of said belt on the surface thereof during said movement, means operated in timed relationship with the operation of said mechanism for delivering articles to said mechanism in predetermined positions about their axes for rotation about said axes, means for positively rotating the article supported by said mechanism to present the entire surface of the article to the belt for finishing operation of said belt thereon, and a device for contouring the belt complementarily to the various contours of the surfaces of the articles against which the belt operates.

3. A surface finishing machine comprising an endless continuously moving finishing belt, mechanism for continuously moving said belt, a jack for engaging and supporting a shoe heel

during operation of the finishing belt on the heel, a device for delivering a shoe heel to said jack in a predetermined position about its longitudinal axis, mechanism for moving the jack parallel with the movement of said belt from and to a stationary and heel receiving position, means for positively turning the heel while it is supported by the jack and during operation of the belt on the heel to provide a surface finish throughout the sides and rear of the heel, and mechanism for causing the belt to operate against the forward corners of the heel at the breast wall thereof to spool or round said corners a desired distance from the top lift end of the heel.

4. A surface finishing machine comprising a continuously moving finishing belt, a reciprocating carriage, mechanism for reciprocating said carriage parallel with the movement of the belt, a jack device supported by said carriage for holding a shoe heel against the belt, mechanism for placing a heel in said jack device in a predetermined position about the vertical axis of said heel preparatory for movement of said jack device by said carriage, mechanism for positively turning said jack device during movement of said carriage to present successively one side, the rear and the other side of the heel against the belt for finishing operation of said belt, and mechanism for shaping the belt in accordance with the adjacent contour of the heel mounted in the jack device.

5. A surface finishing machine comprising a continuously moving finishing belt, a reciprocating carriage, mechanism for reciprocating said carriage parallel with the movement of said belt, a jack device supported by said carriage for engaging and holding a shoe heel for operation of said belt thereon, mechanism for placing a heel in said jack device in a predetermined position about the vertical axis of said heel, and mechanism for positively turning the heel in the jack device to successive positions for said belt to spool one corner of the heel adjacent to the top lift end thereof and to form a surface finish along one side, the rear and the opposite side of the heel and to spool the opposite corner of the heel adjacent to the top lift end thereof symmetrically with said first corner during continuous movement of said carriage.

6. A surface finishing machine comprising a continuously moving finishing belt, a reciprocating carriage, a jack device supported by said carriage for engaging and holding a shoe heel for operation of said belt thereon, mechanism for placing a heel in a predetermined position in said jack device, mechanism for turning the heel in the jack device to successive positions for said belt to spool one corner of the heel adjacent to the top lift end thereof and to form a surface finish along one side, the rear and the opposite side of the heel and to spool the opposite corner of the heel adjacent to the top lift end thereof symmetrically with said first corner during continuous movement of said carriage, and mechanism supported by said carriage for contouring said belt during movement of said carriage as required to operate on the heel, as aforesaid.

7. A surface finishing machine comprising an endless finishing belt, mechanism for continuously moving said belt, a jack device for holding a shoe heel against said belt, mechanism for reciprocating said jack device bodily rectilinearly in one direction from a definite starting position and then in the opposite direction along the same

general plane across and beyond said starting position to a limit of movement and then again to said starting position, means for controlling effective action of said belt on the heel in said jack device during a portion of said movements and for contouring said belt according to the contour of the heel, and means for turning the heel to present the entire side and rear surfaces thereof to the belt for action thereof on the heel during the time that the heel is engaged and moved by the jack device as aforesaid.

8. A surface finishing machine comprising an endless finishing belt, mechanism for continuously moving said belt, a jack device for holding a shoe heel against said belt, mechanism for reciprocating said jack device in a single plane bodily in one direction from a definite starting position and then in the opposite direction in the same general plane across and beyond said starting position to a limit of movement and then again in said plane to said starting position, means for controlling effective action of said belt on the heel in said jack device during a portion of said movements and for contouring said belt transversely according to the longitudinal contour of the heel, means for turning and controlling the heel to present the entire side and rear surfaces thereof only to the belt for sanding action on the heel during the time that the heel is engaged by the jack device, and means for releasing the jack device from the heel at about said limit of movement of said jack device.

9. A surface finishing machine comprising a continuously moving finishing belt, a carriage having a definite starting position, mechanism for reciprocating said carriage in a single plane in one direction from said starting position to a limit of movement and thence in the opposite direction across said starting position to another limit of movement and thence back to said starting position, a jack device supported and moved bodily by said carriage, mechanism for placing a shoe heel in said jack device in a definite predetermined position about the vertical axis of said heel for action of said belt on said heel during first and second movements of said carriage, means for operating said jack device to engage said heel, mechanism for rotating said heel to present first one side and then the rear and then the other side only of the heel against said belt, and means for stripping the heel from the jack device at about said second limit of movement of said carriage.

10. A surface finishing machine comprising an endless finishing belt, mechanism for continuously operating said belt, a reciprocating carriage, a jack device mounted in said carriage for movement adjacent to one side of said belt, means for holding a shoe heel in said jack device, mechanism for moving said carriage and thereby said jack device in one direction from a definite starting position to a limit of movement and thence in the opposite direction across said starting position to another limit of movement and thence back to said starting position, mechanism for turning the heel in said jack device during said first and second movements of said carriage to cause said belt first to finish one corner of the heel and then to impart a surface finish to one side, to the rear and to the opposite side of the heel successively and then to finish the opposite corner of the heel, and mechanism for stripping the heel from said jack devices at about said second limit of movement of said carriage.

11. A surface finishing machine comprising an endless finishing belt, mechanism for continuously operating said belt, a reciprocating carriage, a jack device mounted in said carriage for movement adjacent to one side of said belt, means for holding a shoe heel in said jack device, mechanism for moving said carriage and thereby said jack device in one direction from a definite starting position to a limit of movement and thence in the opposite direction across said starting position to another limit of movement and thence back to said starting position, mechanism for turning the heel in said jack device during said first and second movements of said carriage to cause said belt first to spool one corner of the heel and then to impart a surface finish to one side, to the rear and to the opposite side of the heel successively and then to spool the opposite corner of the heel, mechanism supported by said carriage for contouring the sanding belt against the heel in conformity with the surface of the heel to be spooled or finished by said belt as aforesaid, and mechanism for stripping the heel from said jack device at about said second limit of movement of said carriage.

12. A surface finishing machine comprising a continuously moving finishing belt, a jack device for holding a shoe heel against the belt, mechanism for reciprocating the jack device to and from a definite starting position and for turning the jack device during movement thereof to present successively one side, the rear and the other side of the heel against the belt for finishing operation, mechanism for delivering to said jack a heel turned to a predetermined position about the longitudinal axis, a support for moving said jack device from and to said starting position, and means operated by said support for operating said last-named mechanism to deliver a heel to said jack device.

13. A surface finishing machine comprising a continuously moving finishing belt, a jack device for holding a shoe heel against the belt, mechanism for moving the jack device to and from a definite starting position and for turning the jack device during movement thereof to present successively one side, the rear and the other side of the heel against the belt for finishing operation, mechanism for delivering a heel in a predetermined position to said jack device, a support for moving said jack device from and to said starting position, means operated by said support for causing said mechanism to deliver a heel to said jack device, and means carried by said support for contouring said belt in complement with the various contours of the heel surface during movement of said support and said jack device.

14. A surface finishing machine comprising a movable finishing belt, mechanism cooperating with said belt to support a shoe heel for operation of said belt thereon, means operated by said mechanism for delivering heels thereto at spaced intervals and in predetermined positions about their vertical axes, a device supported by said mechanism for contouring the belt complementarily to the differently curved side and rear surfaces of the heels during operation of the belt against said surfaces, and means for oscillating said device to vary the contour of the belt during movement of the belt and during operation of said mechanism.

15. In a surface finishing machine having a movable finishing belt, and mechanism for supporting a shoe heel for operation of said belt

thereon; a movable frame, means carried by said frame for engaging the top lift end portion of a heel, levers pivoted in said frame for engaging the attaching end portion of the heel and operating to preadjust the heel in said frame in a desired position for delivery to said mechanism, and a device actuated by said mechanism for moving said frame to deliver the preadjusted heel thereto.

10 16. In a surface finishing machine having a movable finishing belt, and mechanism for supporting a shoe heel for operation of said sanding belt thereon; a movable frame, means carried by said frame for engaging the top lift end portion of the heel, levers pivoted in said frame for engaging the attaching end portion of the heel and operating to locate the heel in said frame in proper position for delivery to said mechanism, a movable abutment supported by said frame for engaging the attaching end of the heel, means operated by said mechanism for moving said frame to deliver a heel thereto, and means for disengaging said abutment from the attaching end of said heel automatically and as an incident to engagement of said heel by said mechanism.

15 17. A surface finishing machine comprising a continuously moving finishing belt, mechanism for clampingly engaging opposite ends of and positively turning shoe heels to present successively three sides only, namely one side, the rear and the other side of the heels against the belt for finishing operation, connections for operating said mechanism intermittently to present heels to said belt at spaced intervals, a device operated by said mechanism for delivering heels thereto, and a device supported by said mechanism for contouring the belt complementarily to the contours of the surfaces of the heels against which the belt operates.

20 18. A surface finishing machine comprising a continuously moving finishing belt, mechanism for clampingly engaging opposite ends of and positively turning shoe heels to present successively three sides only, namely one side, the rear and the other side of the heels against the belt for finishing operation, connections for operating said mechanism intermittently to present heels to said belt at spaced intervals, a device operated by said mechanism for delivering heels thereto, a device supported by said mechanism for contouring the belt complementarily to the contours of the differently curved side and rear surfaces of the heels against which the belt operates, and means for regulating said device as required to contour the belt complementarily to the contours of the surfaces of heels of different contours.

25 19. A surface finishing machine comprising a finishing belt, mechanism for continuously moving said belt, a backing belt for said finishing belt, a support, mechanism carried by said support for holding and presenting a shoe heel against said finishing belt for surface finish operation, means operated by said support for moving said backing belt relative to the finishing belt, and a yielding device pressing against said backing belt to shape the finishing belt complementarily to the contour of the surface of the heel against which the finishing belt is operating.

30 20. A surface finishing machine comprising a finishing belt, mechanism for continuously moving said finishing belt, a backing belt for said finishing belt, a support, mechanism carried by

said support for holding and presenting a shoe heel against said finishing belt for surface finish operation, means operated by said support for moving said backing belt relative to the finishing belt, and a yielding device engaging the backing belt and thereby holding the finishing belt against the heel in said last named mechanism.

21. A machine for finishing the surfaces of shoe heels comprising a movable finishing belt, mechanism for supporting and turning a shoe heel to engage surfaces thereof against said belt for operation of said belt on said surfaces to finish the same, a device for holding a heel, lever arms for turning a heel in said device to a predetermined position about the vertical axis of the heel, a device for operating said lever arms to turn the heel to said predetermined position, and means operated by said mechanism for moving said device transversely of the axis of the heel to deliver the heel to said mechanism in said predetermined position.

22. A surface finishing machine comprising an endless finishing belt supported for continuous movement in one direction, mechanism for clamping against opposite ends of and positively turning an article about an axis thereof for operation of the belt upon the surface of said article around said axis, means for moving said mechanism and thereby said article alternately in opposite directions and transversely of said axis of the article during operation of the belt on the surface of said article, and means operated in timed relationship with the operation of said mechanism for delivering an article thereto for clamping engagement and rotation by said mechanism, as aforesaid.

23. A surface finishing machine comprising a movable finishing belt, mechanism for clampingly engaging opposite ends of a solid article and supporting and positively turning about an axis thereof for operation of said belt on the surface of said article around said axis, means for imparting reciprocating movements to said mechanism, and a device operating in synchronism with said reciprocating movements of said mechanism and the turning movement of said article during operation of said belt on said article for contouring the belt complementarily to the contour of the surface of the article against which the belt operates during reciprocating movements of said mechanism.

24. A surface finishing machine comprising a movable finishing belt, a device for supporting and positively turning an article about an axis for operation of the belt on the surface of said article around said axis, mechanism for moving said device in opposite directions from and to a position to receive an article to be supported and turned thereby around said axis, and means operated in timed relationship with the operation of said device for receiving and adjusting articles in predetermined positions about said axis and delivering said articles to said device in said predetermined positions.

5 25. A surface finishing machine comprising a movable finishing belt, a device for engaging opposite ends of and positively turning a solid shoe heel about an axis for operation of the belt on the entire surface of said heel around said axis, mechanism for moving said device in opposite directions from and to a position to receive an article to be engaged and turned thereby around said axis, and mechanism for delivering solid 10 shoe heels to said device in a predetermined position about said axis of said respective heels, whereby said belt will start its finishing operation on the respective heels at approximately the same relative position.

15 26. A surface finishing machine comprising a finishing belt, mechanism for continuously moving said belt, jack mechanism for engaging opposite ends of and holding a shoe heel against said belt, means for moving the jack mechanism alternately in opposite directions from and to a 20 starting position parallel with the movement of said belt and holding the heel against the belt during a portion of said movement of the jack mechanism, and means for positively turning a part of said jack mechanism and thereby turning the heel to present the entire side and rear surfaces only of the heel to the belt for its effective operation on the heel to impart the proper finish to said surfaces during continuous movement of the heel in opposite directions parallel with the movement of the belt.

25 27. A surface finishing machine comprising a movable finishing belt, a device for clampingly engaging opposite ends of and thereby supporting articles for operation of the belt on the surfaces of said articles, means for moving said device alternately in opposite directions from and to a starting position, means for stopping and holding said device stationary in said starting 30 position after each of said movements of said device, and means for rotating the article that is supported by said device about an axis to cause the belt to operate against a portion of the outer surface of said article around said axis during 35 said movement of said device.

40 28. A machine for finishing the surfaces of shoe heels comprising a movable finishing belt, devices for clampingly engaging opposite ends of and thereby supporting heels for operation of the belt on the surfaces thereof, a carriage supporting said devices and being movable alternately in opposite directions from and to a starting position, means for stopping and holding said carriage stationary in said starting position after each of said movements thereof, mechanism for engaging a heel with said devices in a predetermined position about the longitudinal axis of the heel during the time that said carriage is in said stationary position, and 45 means for operating said devices to turn the heels supported thereby about an axis during movement of said carriage.

RAY E. PONDER.
